UNITED STATES PATENT OFFICE.

SAMUEL JOHNSON, OF TOOKELE, UTAH.

WEED-CUTTER.

1,341,804.

Specification of Letters Patent.

Patented June 1, 1920.

Application filed January 20, 1920. Serial No. 352,877.

To all whom it may concern:

Be it known that I, SAMUEL JOHNSON, a citizen of the United States, residing at Tooele, in the county of Tooele and State 5 of Utah, have invented a new and useful Weed-Cutter, of which the following is a specification.

This invention relates to new and useful 10 improvements in devices for cutting weeds, and more particularly to a weed cutter adapted for attachment to cultivators, harrows or the like, to operate in connection therewith.

The primary object of the invention is to 15 provide a device of this character having blades of a particular construction, connected to an auxiliary frame, and so arranged that the same will contact with substantially the entire ground surface, 20 passed over by the harrow or cultivator associated therewith.

A further object of the invention is to 25 provide means for securing the weed cutting blades to the auxiliary frame, so that the same may be readily and easily detached, and attached thereto.

With the foregoing and other objects in 30 view which will appear as the description proceeds, the invention resides in the combination and arrangement of parts and in the details of construction hereinafter described and claimed, it being understood that changes in the precise embodiment of the invention herein disclosed, may be made within 35 the scope of what is claimed, without departing from the spirit of the invention.

Referring to the drawing:

Figure 1 illustrates a plan view of the 40 weed cutter,

Fig. 2 illustrates a side elevational view of the same,

Fig. 3 illustrates a side elevational view of a modified form of a securing device, and

Fig. 4 illustrates a fragmental detail view of the key hole slot.

Referring to the drawing in detail, the reference character 5 designates a transversely extending supporting beam, forming a part of the auxiliary frame, the same 50 being formed of wood or other suitable material.

The supporting yoke, which supports the weed cutting blades, is indicated at 6, and comprises opposed clamping elements 7 and 8, each of which is bent at right angles, to embrace one of the corners of the transversely extending beam 5, so that the same will conform to the contour of the supporting beam to provide means for preventing 60 twisting of the weed cutting blades, with relation to their support.

Each of these clamping members 7 and 8, is also provided with coöperating flanges 9 and 10, the flanges 9, as shown, are of a 65 length to extend substantially the entire width of the supporting beam 5, and are provided with alining openings 11 formed therein, to receive the transversely-extending bolts 12, which bolts also pass through suitable openings formed in the blade beam 13, which is curved as at 14, the lower extremity thereof being formed into an enlargement 15, and apertured as at 16, to receive the securing bolts 17, passing through the openings 16, and through openings formed in the cutting blade 18, whereby the cutting blade is secured to its beam against displacement.

Disposed between the flanges 10, of the 80 yoke, is the beam 19, the same being secured between the flanges by means of the bolts 20, passing through suitable openings in the beam 19 and flange 10, so that the beam 19 is securely clamped between the flange 10. 85 The lower extremity of the beam 19, is also formed into an enlargement 21, and is provided with openings to receive the bolts 22, for securing the forward cutting blade to the auxiliary frame. 90

The construction of the cutting blades, is substantially the same, except that one blade is in the form of a right hand blade, and the other in the form of a left hand blade, however each of the blades includes 95 a substantially flat portion 23, having a curved outer edge 24 which is preferably sharpened to provide a cutting edge, the rear portion of each curved edge 24, extends at an angle to present a shearing action, when the blade is moved through the ground. 100

Adjacent the forward portion of each of the blades, is a depending cutting blade 25,

which extends rearwardly, and inclined rearwardly, from the extreme forward extremity of the respective blades, which cutting blades, embed themselves in the ground surface, and prevent lateral movement of the blades, when the same are in operation. A vertically extending portion 26, forms a part of each of the cutting blades, and is provided with a plurality of openings to receive suitable bolts passing through the beams, so that the cutting blades may be removably secured to their beams, to enable the same to be removed for the purpose of the sharpening, or replacing, in the event 15 that the blades become broken, or otherwise rendered inoperative.

Each of the clamping elements, of the yoke, is provided with an upwardly extending flange 27, which flanges are provided 20 with the key hole slots 28, which slots are constructed to receive the chain 29, employed in securing the plow blades to the frame, and in operation it is to be noted that the chain is moved through the upper portion of 25 the key hole slots, until the same is in proper securing position, whereupon the chain is dropped or moved downwardly into the restricted portions of the key hole slots, where the same is locked against displacement. 30 The forward portion of each of the clamping elements of the yoke, is provided with an opening as at 30, to receive the bolt 31, passing through an opening formed in the right angled end 32, of the securing member 35 33, the rear extremity of each of the securing members 33, extends upwardly as at 34, and is provided with an opening to receive one extremity of the chain 29.

In the modified form of the invention as 40 illustrated by Fig. 3 of the drawings, the cutting blades 18' and 24' are substantially the same as that shown by Sheet 1 of the drawings, except that the depending cutting blades shown by Fig. 2 of the drawings, and indicated at 25 have been eliminated.

The securing mechanism, or yoke, which secures the cutting blades to the supporting beam 5' includes an upwardly extending flange 27' provided with the key hole slot 50 28', the flange 27' being shown as extending upwardly from the beam 5' at a point substantially intermediate the width of the beam.

The clamping element 8' of the yoke is 55 also provided with an opening to accommodate the bolt 9' which is secured to the clamping element 8' by means of the nut 10' operating on the bolt, the bolt 9' having connection with the yoke 11' which includes opposed arms apertured to receive the connecting link 12' of the chain 13'.

From the foregoing it is obvious that I 60 have provided, by the construction described, a securing means adapted to be used 65 in connection with supporting beams of va-

rious sizes, the chain 13' being adapted for use in connection with the walls of the key hole slot 28' for securing the chain 13' against displacement, and at the same time secure the clamping elements of the supporting yoke. 70

In the operation of the device, the device is connected with a harrow or cultivator, to the rear thereof, and operates to cut any weeds or grass, which may be left standing, 75 by the cultivator, or machine to which the same is attached.

Having thus described the invention, what I claim as new is:—

1. In a weed cutting device, a supporting 80 beam, a yoke including opposed clamping members, each of said clamping members having coöperating flanges, cutting blades, beams for supporting the cutting blades, means for securing the cutting blades between the coöperating flanges of the yoke, and means including a chain and key hole slots, for removably securing the yoke to the supporting beam.

2. In a weed cutting device, a supporting 90 beam, a yoke including opposed clamping members, the clamping members being formed to embrace one edge of the supporting beam, weed cutting blades having means coöperating with the clamping members for 95 securing the cutting blades to the yoke, right angled flanges forming a part of each yoke, each of the right angled flanges having a key hole slot, a securing member having connection with each of the opposed clamping 100 members, a chain having connection with the securing members and passing through the key hole slots, the chain embracing the rear of the supporting beam, and means for removably securing the securing members to 105 the yoke.

3. In a weed cutting device, a supporting beam, a yoke including opposed clamping members embracing the forward portion of the supporting beam, adjustable means embracing the rear of the supporting beam, for securing the yoke thereto, weed cutting blades supported by the beam, each of the weed cutting blades including a curved cutting edge, and a depending cutting blade 110 formed adjacent the forward portion of the cutting blades, the depending cutting blade, having its lower edge inclined toward the front of the weeding cutting blade.

4. In a weed cutting device, a supporting 120 beam, a yoke including opposed clamping members, each of said clamping members having an upwardly extending flange, each of said flanges having a key hole slot formed therein, securing members, each of said securing members having connection with the yoke, and extending transversely of the beam, and in contact with the under surface thereof, said securing members having an upwardly extending end embracing the rear 125 130

lower corner of the beam, for preventing movement of the securing members with relation to the beam, and adjustable means having connection with the securing members and passing through the key hole slots, for securing the yoke to the supporting beam.

In testimony that I claim the foregoing as my own, I have hereto affixed my signature in the presence of two witnesses.

SAMUEL JOHNSON.
